UNITED STATES PATENT OFFICE

2,508,994

OVERSHOE WITH REAR OPENING AND
TONGUE THEREINKenneth C. Demick, Cambridge, Mass., assignor
to The B. F. Goodrich Company, New York,
N. Y., a corporation of New York

Application June 28, 1947, Serial No. 757,751

4 Claims. (Cl. 36—7.3)

1

This invention is concerned with an article of footwear such as an overshoe or the like of the rear-opening type. More particularly, the invention is concerned with a rear-opening overshoe provided with a tongue adapted to act as a shoe horn to aid in donning the overshoe.

The objects of the invention include providing an overshoe of the rear-opening type which may be donned without the necessity for soiling the hands, providing an overshoe in which the uppers may be opened sufficiently to permit ready donning and doffing, providing an overshoe having as an integral part thereof means for guiding the shoe into proper position in the overshoe and particularly for guiding the heel of a shoe into the heel pocket, and generally providing an overshoe combining serviceability and pleasing appearance. Other objects will be apparent from the description which follows.

In general, an overshoe embodying this invention comprises uppers and sole portions joined together in a unitary structure in which the uppers is split down the back from the top thereof to the top of the heel pocket, the uppers having closure means for the slit rear zone and having a tongue positioned inside the slit rear zone with a lower portion of the tongue secured to the uppers across the slit and the upper portion of the tongue unsecured to the uppers.

The invention is best understood by reference to the accompanying drawings.

Of the drawings:

Fig. 1 is a rear view in elevation of an overshoe embodying the invention with the upper portion closed;

Fig. 2 is a rear view in elevation of the overshoe in condition for donning and doffing; and

Fig. 3 is a section on line 3—3 of Fig. 2.

An overshoe constituting a preferred embodiment of the invention as shown in Fig. 1 consists of sole 10 and uppers 11 portions joined together in a unitary structure. The overshoe has a relatively deep heel pocket 12 with a heel bulge 13 above pocket 12 to conform to the contour of the wearer's shoe, the overshoe having a form-fitting ankle-encircling portion 14. The uppers 11 is divided along a rear zone by a slit 15 which extends downwardly from the top 16 of the uppers and terminates short of the bottom of the heel pocket 12, preferably terminating near the top of the heel pocket.

Uppers 11 is provided with suitable closure means adapted to hold the edges of the divided rear zone in abutting relation, the closure means

2

preferably comprising a slide fastener 17 secured to the uppers 11 along the edges of the slit 15.

A tongue 18 is positioned inside the divided rear zone of uppers 11. The lateral edges of the lower portion of tongue 18 are secured to uppers 11 on the respective sides of slit 15 from at least the lower end of slit 15 to the top of heel bulge 13. The upper portion of tongue 18 is unsecured to uppers 11, and tongue 18 extends substantially the entire length of slit 15.

The entire tongue is of inelastic material, and the central zone 19 of the lower portion is relatively stiff while the remainder of the tongue is relatively flexible. The lower portion of tongue 18 is of sufficient width to allow the uppers to be spread out to a considerable extent while donning or doffing the overshoe. The excess width of the tongue folds into generally V-shaped bellows pockets on each side of the stiff central zone 19 when the rear of the uppers is closed.

Tongue 18 preferably comprises flexible textile fabric which may be waterproofed if desired. Central zone 19 of tongue 18 is preferably stiffened by an insert of stiff duck fabric extending from the lower end of tongue 18 up to the point where the longitudinal edges of the tongue are unsecured to the upper, i. e., to the top of the heel bulge. The stiffened central zone may be formed by any suitable stiffening means as for example by impregnating or coating a central zone of the tongue with resinous material. This central zone serves as a shoe horn to guide the heel of the shoe into the heel pocket and thus to secure correct positioning of the shoe in the overshoe. The reinforced central zone is extended to the height at which the heel of a shoe first contacts the tongue and prevents undue abrasion of the tongue.

Slit 15 terminates near the top of the heel pocket 12 so that the shoe heel must slide into the proper place in the pocket with the aid of tongue 18. Since tongue 18 serves as a shoe horn, it is not necessary or desirable to extend slit 15 to the bottom of heel pocket 12. Since slit 15 terminates at the top of heel pocket 12, the shoe heel sliding along tongue 18 is always in correct position upon entering pocket 12 and this also forces the toe of the wearer's shoe into the toe portion of the overshoe without the necessity of the wearer soiling his hand by pulling on the sole of the overshoe.

Tongue 18 is secured to uppers 11 up to the top of heel bulge 13 so that the tongue is supported by the uppers throughout the entire zone in which the shoe heel is in contact with the tongue and

55

exerting pressure thereon. Thus, pressure on the tongue in this region tends to pull the overshoe onto the shoe. The unsecured upper tongue portion allows the person donning the overshoe to grasp the tongue easily and pull the overshoe on over the shoe without soiling his hands.

Since the tongue is adapted to act as a shoe horn, it must necessarily be of inelastic material. The fullness necessary to allow the uppers to be opened beyond its normal condition is provided by the bellows pockets of the lower portion of the tongue. The tongue is preferably extended substantially to the top of the uppers so that it also serves as a guard inside the closure means.

When the overshoe is being worn, the edges of the divided rear zone of the upper are held in abutting relation by the closure means and the tongue is entirely hidden inside the uppers so that the overshoe presents a neat and pleasing appearance.

The invention has been described in detail with reference to an overshoe which constitutes a preferred embodiment thereof, but the invention may be embodied in any rear-opening article of footwear where it is desirable to provide means integral therewith for guiding the shoe of the wearer into the article.

Variations and modifications may be effected within the spirit and scope of the invention as defined in the appended claims.

I claim:

1. An overshoe having an upper extending above the ankle and opening along a slit extending downwardly from the top margin in the rear of the overshoe, said slit terminating short of the bottom of the heel pocket, a shield member adapted to act as a shoe horn underlying substantially the full length of the slit along the inner face of the upper and secured to said upper along both sides of said slit from the bottom thereof to approximately ankle level and extend-

ing upwardly free of the upper as a relatively narrow elongated tongue above said level, reinforcing means for stiffening the central zone of said shield member from approximately the bottom thereof to at least ankle level, and closure means for closing said slit.

2. The overshoe of claim 1 in which a bellows pocket is provided at each side of said shield member in the zone secured to the upper.

10 3. An overshoe having an upper extending above the ankle and opening along a slit extending downwardly from the top margin in the rear of the overshoe, said slit terminating short of the bottom of the heel pocket, a shield member adapted to act as a shoe horn underlying substantially the full length of the slit along the inner face of the upper and secured to said upper along both sides of said slit from the bottom thereof to approximately ankle level and extending upwardly free of the upper as a relatively narrow elongated tongue above said level, a stiffening member secured to the central zone of said shield member from approximately the bottom thereof to approximately ankle level, and closure 15 means for closing said slit.

20 4. The overshoe of claim 3 in which a bellows pocket is provided at each side of said tongue member in the zone secured to the upper.

KENNETH C. DEMICK.

Certificate of Correction

Patent No. 2,508,994

May 23, 1950

KENNETH C. DEMICK

It is hereby certified that error appears in the printed specification of the above numbered patent requiring correction as follows:

Column 4, line 27, for the word "tongue" read *shield*;
and that the said Letters Patent should be read as corrected above, so that the same may conform to the record of the case in the Patent Office.

Signed and sealed this 3rd day of October, A. D. 1950.
